DESIGN FOR AN AIRPLANE

Igor I. Sikorsky, Long Hill, Conn.

Continuation of application Serial No. 49,546,
October 25, 1933. This application June 5,
1935, Serial No. 57,138

Term of patent 7 years

To all whom it may concern:

Be it known that I, Igor I. Sikorsky, a citizen of the United States, residing at Long Hill, in the county of Fairfield and State of Connecticut, have invented a new, original, and ornamental Design for an Airplane, of which the following is a specification, reference being had to the accompanying drawing, forming part thereof.

Figure 1 is a top perspective view of my design,
Figure 2 is a bottom perspective view,

Figure 3 is a front elevation shown on a reduced scale.

This application is a continuation in part of my co-pending application Serial No. D-49,546 filed October 25, 1933.

I claim:

The ornamental design for an airplane, as shown.

IGOR I. SIKORSKY.
